UNITED STATES PATENT OFFICE.

HENRY L. MORIN, OF DETROIT, MICHIGAN.

SCRAPER FOR WRINGERS.

Original application filed February 6, 1926, Serial No. 86,600. Divided and this application filed September 20, 1927. Serial No. 220,792.

This invention relates to clothes wringers, and particularly to an improved scraping attachment therefor, and has for an object to provide an improved construction whereby the wringer may be used intermittently or continually, and the clothes prevented from wrapping around the squeezing rollers.

Another object of the invention is to provide a system of scrapers in connection with a wringer having a safety device or without the safety device, the scraping structure being such as to prevent the clothes passing through the wringer from adhering to the rollers.

15 A further object, more specifically, is to provide a scraping attachment for wringers, wherein the scraping members are either weight actuated or spring actuated.

This application is a divisional application 20 of my prior application, Serial No. 86,600, filed Feb. 6, 1926.

With the above recited and other objects in view, the invention resides in the novel construction set forth in the following 25 specification, particularly pointed out in the appended claims and illustrated in the accompanying drawings, it being understood that the right is reserved to embodiments other than those actually illustrated herein, 30 to the full extent indicated by the general meaning of the terms in which the claims are expressed.

In the accompanying drawings—

Figure 1 is a side view of a wringer with 35 scraping structures embodying the invention shown applied thereto.

Figure 2 is a rear view of part of the wringer shown in Figure 1, with the scrapers embodying the invention shown associated therewith.

40 Figure 3 is a top plan view of the structure shown in Figure 1.

Figure 4 is a sectional view through Figure 3, approximately on line 4—4.

45 Figure 5 is a detail fragmentary view similar to the structure shown at the left in Figure 4 but illustrating a modified arrangement of scrapers.

Figure 6 is a fragmentary sectional view 50 similar to Figure 4, but showing a modified form of scrapers wherein weights are used instead of springs.

In applying an embodiment of the invention 55 to a wringer, it will be noted that the same may be applied to any of the wringers

now in common use, or to a wringer of the kind shown in my co-pending application, Serial No. 86,600.

Referring to the accompanying drawings by numerals, 1 indicates a support of any desired kind on which a wringer 2 is mounted. The wringer 2 is provided with brackets 3 which may be specially secured thereto by screws or otherwise and which fit into notches 4 in the extensions 5 on the side bars 6 of frame 6. The frame 6 is provided with two side bars constructed as shown in Figures 1 and 2 and with suitable connecting and bracing bars 7 held in place by suitable nuts.

70 It will be noted from Figure 4 that nuts are provided on the bar 7 for spacing the side bars of frame 6. Rollers 8 and 9 are rotatably mounted on the frame 6, roller 8 having end plates or flanges 10 for holding the belt 11 in place and also for assisting in guiding the clothes as they are fed through the device. The belt 11 may be a combination of canvas and rubber or other desired material, and is held taut by suitable springs 80 12 arranged in sockets 13 on the respective side bars of frame 6. These springs act on journal blocks 13', which press against the shaft 14 supporting the roller 8. A cross bar 15 is connected in any suitable manner with the extensions 5, said cross bar supporting a scraper 16 and a guiding plate 17. The scraper 16 may be made of a combination of rubber and canvas or other desired material and acts to in a certain sense, scrape 90 or prevent clothes from following the belt 11 around the roller 9. This scraper insures all of the clothes passing over belt 11 engaging the plate 17 and then the roller 18 of the wringer 2. The plate 17, together with the 95 scraper 16, acts as a bridging structure for bridging the space between the rollers 9 and 18.

100 In order to prevent thin pieces of clothes or in fact, any piece of clothes from adhering to the rollers 18 and 18', there are provided scrapers 19 and 20 made of any desired material, but preferably of rubber. These scrapers are clamped by bolts or otherwise to swinging arms 21 and 22. It will be 105 noted that there are two arms 21 and two arms 22, and these respective arms are bolted or otherwise secured to the respective metallic holders 23 and 24 gripping the scrapers 19 and 20. The arms 21 are preferably piv- 110

totally held in place by the respective pivotal pins 25 which hold the swinging frame 26 on an extension 27 of frame 6. A retractile spring 28 is connected to frame 6 for each 5 of the arms 21 and at one end is connected to these arms for normally holding the scraper 19 against the roller 18'. Each of the arms 21 is also provided with a forwardly extending portion 29 (Figure 1) formed 10 with a bent over section 30 adapted to be engaged by the thumb when it is desired to raise the scraper 19 off of the roller 18'. The arms 22 are yieldingly held against the roller 18 by springs 31 connected to the 15 respective arms and to the cross bar 15. Each of the arms 22 is provided with a forwardly extending section 32 which may be engaged by the hand of the operator and moved upwardly for swinging the scraper 20 away from roller 18. It will thus be seen that as the clothes are fed through the wringer, the scrapers 19 and 20 continually function to prevent any of the clothes from adhering to the rollers and, consequently, 25 causing the rollers to continually function in a desirable manner. It will also be evident that the scrapers 19 and 20 may be connected to a stationary part of the wringer instead of to the frame 6 as illustrated 30 in Figure 5. From this figure, it will be noted that the scrapers function to remove the clothes from the rollers but are pivotally mounted on the wringer 2 and held in operative position by suitable springs.

35 In providing the scrapers, it is aimed to produce a very practical construction for wringers of any desired kind which will not dig into the wringer rollers, and which will not appreciably wear said rollers. In the 40 present construction, the scraper is preferably made of a good grade of rubber which will bend over slightly when the wringer is in motion, and will cause the scraper to always present a sharp or straight edge to the rollers. The springs act to provide the 45 desired pressure so that when the wringer is in use, the edge of the scraper will be deflected and slightly bent over to produce a sufficient scraping action that will stop a 50 thread or even thin tissue paper from winding around the rollers. This action will, of course, keep clothes from winding around the rollers and, consequently, cause the

clothes to be discharged after having been wrung. Under some circumstances, the 55 scrapers could be made of heavy canvas or other soft and substantially resilient material, though rubber has been found to be very desirable as it has the desired characteristics and will wear an appreciable time. 60

In Figure 6, a modified form is presented wherein the arm 21' is made comparatively heavy so that the scraper 19 will act through gravity instead of spring 28. The arm 22 is provided with a weight 32' which may be 65 adjustably positioned so as to give varying pressures on the scraper 20. The weight of the respective parts is such that the scrapers 19 and 20 will be deflected or bent over slightly at their contact edges in similar 70 manner to the action produced by the springs 28 and 31. In this form of the invention, preferably the scraper 19 is at the highest point on roller 18' and scraper 20 is at the lowest point on roller 18. 75

What I claim is:

1. In a clothes wringer provided with a pair of squeezing rollers, a flat rubber scraper for each roller, a swinging arm for each scraper, said arms being pivoted so that the 80 scrapers will move in a direction substantially toward the center of the rollers with the scrapers extending substantially radially, and means acting on the arms for producing sufficient pressure thereon to cause the edges 85 of the scrapers to bend when the rollers rotate whereby an efficient scraping action is secured and articles are prevented from adhering to the rollers.

2. In a clothes wringer provided with a 90 pair of squeezing rollers, a scraping structure associated with each roller, each of said scraping structures including a thin flat flexible scraper blade, a pair of holding plates carrying said blade, means for removably 95 clamping said blade to said holding plates, a pivotally mounted arm connected at one of its ends with said plates whereby the blade may swing toward and from one of said rollers, and a spring acting on said arm 100 for causing the plates to press said blade against said roller.

Signed at Detroit in the county of Wayne and State of Michigan, this 17th day of September, A. D. 1927.

HENRY L. MORIN.
